UNITED STATES PATENT OFFICE.

HERMAN MAYER, OF NEW YORK, N. Y.

DESIGN FOR A CLOAK.

SPECIFICATION forming part of Design No. 35,849, dated April 1, 1902.

Application filed January 17, 1902. Serial No. 90,224. Term of patent 3½ years.

To all whom it may concern:

Be it known that I, HERMAN MAYER, a citizen of the United States, and a resident of New York city, county and State of New York, have invented a new and original Design for Cloaks, of which the following is a specification, reference being had to the accompanying drawings, in which—

Figure 1 is a front view of my newly-designed cloak; Fig. 2, a rear view thereof; and Fig. 3, a cross-section on line 3 3, Fig. 1.

As shown in the drawings, the leading feature of the design consists of a cloak A, having a cape a, that projects over the shoulder-pieces of the garment. The cape has a concave edge over each shoulder, such edge terminating in a V-shaped point a². Set back

from the front points there extends downward to the bottom of the garment a pair of front flaps a³, which taper from top to bottom. A corresponding tapering rear flap extends from the rear points down to the bottom. The cape and flaps are connected to and form part of the garment.

What I claim is—

The design for a cloak, substantially as herein shown and described.

Signed by me at New York city, county and State of New York, this 16th day of January 1902.

HERMAN MAYER.
